UNITED STATES PATENT OFFICE.

GEORGE J. WILLIAMS, OF PHILADELPHIA, PENNSYLVANIA.

COMBINATION KNOCKDOWN TOOL.

Application filed September 13, 1924. Serial No. 737,504.

To all whom it may concern:

Be it known that I, GEORGE J. WILLIAMS, a citizen of the United States, residing at 3132 Market Street, Philadelphia, in the 5 county of Philadelphia and State of Pennsylvania, have invented new and useful Improvements in Combination Knockdown Tools, of which the following is a specification.

10 My invention relates to new and useful improvements in a combination knockdown tool and has for its primary object to provide a tool of this character which will combine a level, square, plumb rule, straight 15 edge, and spirit plumb so that there are practically five tools in one.

Another object of my invention is to so construct the tool that the same will be formed of a number of sections which may 20 be disconnected for packing and so occupy a relatively small space or connected in different ways to produce different tools.

25 A further object of this invention is to provide fastenings of unique construction for the several sections whereby they will be firmly held in their operative positions.

With these ends in view, this invention consists in the details of construction and combination of elements hereinafter set 30 forth and then specifically designated by the claims.

In order that those skilled in the art to which this invention appertains, may understand how to make and use the same, I will 35 describe its construction in detail, referring by numerals to the accompanying drawings forming a part of this application, in which:—

40 Fig. 1 is an isometric view of my combination knockdown tool, showing the sections connected for use as a level, straight edge, plumb rule or spirit plumb.

Fig. 2 is a similar view showing how the sections are connected for use as a square.

45 Fig. 3 is an enlarged broken side elevation of one of the end sections illustrating details of construction.

Fig. 4 is an edge view thereof partly in section.

50 Fig. 5 is an enlarged end view of the intermediate or central section.

Fig. 6 is a broken side elevation thereof.

Fig. 7 is an edge view of the same partly in section.

55 Fig. 8 is an enlarged fragmentary edge view of the tool when used as a square.

Fig. 9 is a side elevation thereof, partly in section.

Fig. 10 is a fragmentary sectional edge view of the tool, illustrating the connection 60 or joint between two sections when in endwise alignment.

In carrying out my invention as herein embodied, 2 represents the tool as a whole, consisting of a plurality of sections which 65 for convenience of illustration are here shown as three in number, designated by the numerals 3, 4 and 5.

An intermediate section 4 comprises a substantially rectangular body, having a lug 70 6 at one or both ends of less size than the cross sectional area of the body, and in each of these lugs or projections is formed a transverse T slot 7, Figs. 6 and 7 for the reception of the T rib 8 on the outer end of 75 the sliding block 9, said T rib being slidable into the T slot.

One of these sliding blocks 9 with its T rib is mounted in a recess 10 at the inner end 80 of each end section and said recess is of sufficient length to house the sliding block 9 and one of the lugs or projections 6 on an intermediate section. The sliding block carries a screw rod 11 which passes through a pair of associated spaced parallel partitions 12, with 85 its end projecting into a bore 13 leading from the recess 10, said bore being of sufficient length to accommodate the major portion of the screw rod 11. The end of the screw rod which enters the sliding block 9 is preferably polygonal in cross section to 90 prevent rotation of said screw rod relative to the sliding block, and in order to secure these two parts together, a pin 14 may be driven into the sliding block and through 95 the screw rod. An adjusting nut 15 has threaded connection with the screw rod 11 and is positioned between the two partitions 12 and held thereby against endwise movement.

100 From this portion of the description it will be readily noted that when the sliding block 9 is moved out, as shown in Fig. 4, by revolving the adjusting nut 15 in the proper direction, to which access is had through the opening 16, the T rib 8 may be slipped into the T slot 7 in a projection 6 at the end of an intermediate section; then, by reversing the 105 rotation of the adjusting nut 15, the sliding block 9 will be drawn into the recess 10, pulling the projection 6 along with it into said recess until the coacting ends of the two sec- 110

tions butt each other, thus firmly holding the two sections together.

Although after the lug 6 has been drawn into the recess 10 there can be no movement 5 of one section relative to the other, I desire to provide additional means to insure against lateral movement of one section relative to the other, and therefore a tongue 17 is provided in the inner end of each end 10 section for registration with a groove 18 at each end of an intermediate section.

One of the end sections, as 3, is provided with a T groove 19 along one of its edges at its outer end, so that said groove is open in 15 the outer end of the section 3. This provides for the other end section being attached to the outer end of the end section 3 by sliding the T rib 8 on the sliding block 9 in the end section 5 into the T groove 19 and then 20 drawing the sliding block into the end section 5 until its inner end abuts the edge of the end section 3, as plainly shown in Figs. 2, 8 and 9. When brought into the abutted relation the tongue 17 on the end section 5 25 will enter the groove 20 in the edge of the section 3 crosswise of the T groove 19, thus properly aligning the two sections to form the square part in Fig. 2.

In addition to the openings 16 in the end 30 sections wherein are located the adjusting nuts, all or some of said sections are provided with other openings 21, wherein are located the spirit glasses 22, and as will be obvious and therefore not explained in detail, these spirit glasses are of ordinary construction, and some are in transverse positions while others are in longitudinal positions with relation to the tool when connected as shown in Fig. 1.

40 All of the openings 16 and 21 pass entirely through the body of the section in which they are formed so as to be visible or accessible from either face or side of the tool, and in order to protect the portion within the 45 openings against breakage when not in use and also prevent the accumulation of dirt in said openings, the latter may be closed by suitable covers 23.

Although I do not wish to be limited to 50 the particular construction or arrangement of these covers, a satisfactory method of mounting such covers consists in providing a frame 24 which is embedded in the body of the section, each frame including two bezels 25 and 26 joined by a neck 27, the latter comprising two spaced bars. Between the bars of the neck is pivoted the tail 28 and the cover 23, thereby permitting said cover to be swung into either of the bezels 55 25 or 26, it being understood that one of these surrounds an opening 16 or 21, so that when the cover is in one bezel, said cover will close one end of the opening, but when 60 swung over into the other bezel, said cover will lie flush with the face of the tool so as

not to interfere with the proper use of the tool. In order that the cover shall be held in either the open or closed position, a spring 29 is associated with the tail 28 so as to lie against either face of said tail according 70 to the position of the cover.

One of the end sections, as 3, has a number of notches 30 formed in its outer end into which is laced the end of the plumb line 31, carrying the plumb bob 32, the latter being 75 so positioned as to partially enter the plumb bob opening 33, and in order that the workman shall know when the line is straight or plumb, a center line 34 is formed on each section in any suitable well known manner. 80

One of the sections, as 3, is provided with a hand hole 35 whereby the tool may be easily and readily handled. In practice, when the sections of the tool are joined together in endwise alignment, as shown in 85 Fig. 1, said tool may be used as a level by viewing the spirit glass, which is arranged longitudinally of the tool. By using the tool in a vertical position and viewing transverse, spirit glass or glasses shall then act as a spirit plumb. The tool may also be used as a straight edge in any position. When the plumb line and bob are attached, the tool may then be used as a plumb rule. 90

When it is desired to use the tool as a square, as shown in Fig. 2, one of the end sections, as 5, is connected to the outer end of the other end section 3, so as to project from one edge thereof. 95

Of course, I do not wish to be limited to 100 the exact details of construction herein shown and described, as these may be varied within the limits of the appended claims without departing from the spirit of my invention.

Having thus fully described my invention, what I claim as new and useful is:

1. A tool comprising an intermediate section and two end sections, a lug at each end of the intermediate section, said lug having a T-shaped groove therein; each of said end sections having a recess in the inner end, an opening crosswise thereof and communicating with the recess and a bore leading from said recess, a sliding block mounted in the recess, a T shaped rib on the block for registration with the groove in a lug on the intermediate section, a screw rod attached to the block and movable into the bore, a pair of partitions across the recess and through which the screw rod passes, and an adjusting nut having threaded connection with the screw rod and positioned between the partitions and accessible through the opening, the revolving of said nut drawing the sliding block and lug into the recess until the connected sections abut. 115

2. A tool comprising an intermediate section and two end sections, a lug at each end 120 of the intermediate section, said lug having 125

a **T** shaped groove therein, each of said end sections having a recess in the inner end, an opening crosswise thereof and communicating with the recess and a bore leading from 5 said recess, a sliding block mounted in the recess, a **T** shaped rib on the block for registration with the groove in a lug on the intermediate section, a screw rod attached to the block and movable into the bore, a pair 10 of partitions across the recess and through which the screw rod passes, and an adjusting nut having threaded connection with the screw rod and positioned between the partitions and accessible through the opening, the 15 revolving of said nut drawing the sliding

block and lug into the recess until the connected sections abut, one of said end sections further having a **T** shaped groove in one edge running longitudinally, and open at the outer end of said end section for the reception of the rib on the block of the other end section when the tool is used as a square, and tongues on the inner ends of the end sections for registration with grooves in the ends of the intermediate section and a groove in the 20 edge of one of the end sections.

In testimony whereof, I have hereunto affixed my signature.

GEORGE J. WILLIAMS.
